UNITED STATES PATENT OFFICE.

JOHN M. PECK, OF NEW HAVEN, CONNECTICUT, ASSIGNOR TO PECK BROTHERS & CO., OF SAME PLACE.

FAUCET.

SPECIFICATION forming part of Letters Patent No. 247,402, dated September 20, 1881.

Application filed August 23, 1880. (No model.)

To all whom it may concern:

Be it known that I, JOHN M. PECK, of New Haven, in the county of New Haven and State of Connecticut, have invented an Improvement 5 in Faucets; and I do hereby declare the following, when taken in connection with the accompanying drawing and the letters of reference marked thereon, to be a full, clear, and exact description of the same, and which said 10 drawing constitutes part of this specification, and represents a vertical central section through the discharge-spout.

This invention relates to an improvement in that class of faucets for basins and similar purposes in which the discharge-spout is arranged close down to the slab, and commonly known as "low-down" faucets. A serious difficulty has been experienced in this class of faucets, 15 because of the impossibility of getting at the valve to replace or repair it without detaching the faucet entirely from its seat.

The object of this invention is to overcome this difficulty; and it consists in the construction hereinafter described, and particularly re- 20 cited in the claim.

A is the discharge-spout, extending from the base of the vertical shell B.

C is the connection with the supply-pipe, which opens into a passage, D, in the shell.

W is the body, constructed with a valve-seat 30 at its lower end to enter and take a seat upon the inlet-passage D, as at a, and also to take a bearing on the outer shell, B, as at d, with one or more ports or openings, G, from the water-way and between the two bearing-points a d. 35

T is the valve-stem, hung upon an eccentric or otherwise in the body W, and provided at its lower end with a valve, P, and so that the valve may be thrown down to open or raised to close, in the usual manner, too well known 40 to require description in this application, the essential feature of the invention being the peculiar connection of the body W to the parts below.

I claim—

In a faucet having a valve arranged upon a spindle operating vertically, the body W, entering the water-way from above, and having two seats, a d, with one or more ports, G, substantially as described. 45

JOHN M. PECK.
